Primary Examiner — Darlington Ly*Assistant Examiner* — D. Ryan Tisdale(74) *Attorney, Agent, or Firm* — WHDA, LLP(57) **CLAIM**

The ornamental design for a wheel for an automobile, as shown and described.

DESCRIPTION

FIG. 1 is a perspective view of a wheel for an automobile, showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational thereof; and,

FIG. 7 is a left side elevational view thereof.

The ghosted showing of the barrel, rim hub, lug holes and valve stem hole illustrate portions of the wheel for an automobile that form no part of the claimed design.
